CHILD'S COASTER TOY

Jack J. de Roco, 15653 Cranbrook St.,
San Leandro, Calif.

Filed Oct. 22, 1964, Ser. No. 82,286

Term of patent 14 years

(Cl. D34—15)

FIGURE 1 is a top plan view of the child's coaster toy showing my new design.

FIGURE 2 is a side elevation of the coaster when looking at the left hand side of FIGURE 1.

FIGURE 3 is another side elevation of the coaster when looking at the right hand side of FIGURE 1.

FIGURE 4 is a bottom plan view of the coaster.

FIGURE 5 is a front elevation of the coaster.

FIGURE 6 is a rear elevation of the coaster.

I claim:

The ornamental design for a child's coaster toy, substantially as shown.
